METHOD OF PACKING FINNED PIPE FOR
SHIPPING AND HANDLING

Alpheus O. Hurxthal, Wyndote, and George W. O'Keeffe, Elkins Park, Pa., assignors to Proctor & Schwartz, Inc., Philadelphia, Pa., a corporation of Pennsylvania

Application September 4, 1946, Serial No. 694,790

6 Claims. (Cl. 206—46)

1

This invention relates to the packing of finned pipe for shipping, handling, and storing purposes; and to an article of commerce resulting from the method and the means employed in the packaging of the finned pipe.

Finned pipe, as well known in the art, comprises a length of metal pipe of circular or other contoured cross section, with metal plates or spaced convolutions of a continuous thin metal strip disposed on the outer surface of the pipe, in either case, with the inner edge of the plates or the strip in heat-conducting contact with the outer surface of the pipe, and with the body of each plate or the strip standing substantially perpendicular to the axis of the pipe, leaving the outer edges of the plates or strip fin-forming elements exposed and unprotected.

The outer unprotected edges of the fin-forming elements frequently become bent or otherwise injured during handling, storing or shipping, as a result of the completed finned pipe units making contact with each other or by being struck by some extraneous object.

Prior to the present invention, it has been customary to protect the fin structure on the pipe by encasing the completed units in boxes or crates, either separately or with a number of units in a common container, and by providing means for supporting the separate units in a manner to prevent the units making contact with each other in the common container.

The common containers usually consist of a wooden box or crate having a rack built therein to keep the units separate. As a result of the present lumber shortage, it has been difficult to secure the necessary lumber for the crates. Under the circumstances, the cost of the lumber and labor employed in packaging the completed units amounts to substantially 20 per cent of the cost per foot of the complete units.

One object of the present invention is to provide a package for, and a method of packaging finned pipe which will facilitate the packing operation and afford full and complete protection for the fin structure on the pipe, at a greatly reduced cost, and which will not require the use of scarce lumber or the employment of a great amount of labor as now required under the prior practice to construct crates and enclose the finned pipe units therein.

In the accompanying drawing:

Fig. 1 illustrates a complete finned pipe unit packaged in accordance with the present invention for handling, shipping, and storing purposes, etc.;

2

Fig. 2 is an enlarged fragmentary longitudinal sectional view of the package illustrating the manner in which the edges of the fins are protected in the event of the package being struck by an extraneous object;

Fig. 3 is an enlarged longitudinal sectional view illustrating a modified arrangement for closing the end of the package around the unit;

Fig. 4 is an end view illustrating a plurality of the units shown in Fig. 1 assembled for shipping and other purposes; and

Fig. 5 is a view illustrating a modification of the invention wherein the package is built directly on and in contact with the outer edges of the fins.

As shown in the drawing, the specific form of fin pipe unit employed herein for the purpose of illustrating the invention comprises a hollow pipe of circular cross section, indicated at 1. Extending circumferentially and longitudinally of the pipe 1 is a multiplicity of longitudinally spaced convolutions 2, 2 composed of a thin metal strip spirally wound on the outer surface of the pipe 1 and, in the present instance, with the inner edge of the strip 3 bent at right angles to the radially extending body portion of the strip to form a flange or foot 4 thereon, to provide maximum heat conductivity from the pipe 1 to the fins 2, or vice versa.

Normally, the outer edges 5 of the convolutions 2 of the strip 3 are exposed and unprotected. In order to afford protection for these outer edges of the fins, in accordance with the present invention, the entire length of the fin structure on the pipe 1 is encased within a sleeve or tube 10 which may be of metal, plastic, vulcanized fiber, paper, or ordinary cardboard, such, for example, as that employed in the making of mailing tubes.

Preferably, the tube 10 is composed of cardboard of medium density and of any desired wall thickness. The finned unit should fit fairly snug or close within the outer casing provided by the tubing 10, whereby the force of any contact of the tube 10 with any extraneous object will be distributed across the outer edges of a large number of the fins 2. The contact of the inner surface of the tube 10 with such a large number of the outer edges of the fins 2 will prevent injury to the outer edges of any small group of such edges and afford protection thereto against indentations being produced in the outer tube 10 by localized contact with some extraneous object.

The wall thickness of the tubing 10 may vary and the quality of the stock in the tubing likewise may vary without departing from the spirit

of the invention. It is preferred, however, to employ a paper tubing of medium density which will be sufficiently tough to resist tearing under ordinary handling circumstances.

The quality of the stock and the thickness and density of the wall of the tube 10 should be such that, should the packaged unit be struck by some extraneous object, the outer edges 5 of the fins 2 would impress themselves in the wall of the tubing 10, as illustrated at 11 in Fig. 2, without cutting through the tubing, and form small convexities 12 between the adjacent relatively spaced fin edges 5, 5, which will suffice to maintain the edges 5, 5 in their spaced relation to each other, and connect the fins to each other at the outer edges thereof. Thus, the combined inherent bend-resisting forces of the connected fins will collectively resist lateral bending of any and all of the fins within the area struck by the extraneous object, within reasonable limits normally encountered.

While a single outer casing tubing 10 may be employed to cover the total length of the fin structure of any one unit, it is desirable, with units of the longer lengths, for example, units of approximately fifteen feet, to employ a plurality of tube structures 10a, 10a applied to the outside of finned pipe unit in end-to-end abutting relation to each other, for collectively covering the entire length and circumference of the fin structure, from end-to-end thereof; and to connect the abutting ends of the sections 10a, 10a by overlapping bands 13, 13 of gummed adhesive fabric or paper tape, as shown in Fig. 1.

In a like manner, in order to avoid relative axial shifting of or excessive axial movement between the outer casing 10 and the fin structure made up of the fins 2, 2 encased thereby, similar tapes 14, 14 are wound around the terminal ends of the outer casing tubing 10 with said tapes dropping over the ends of the fin structure and being also wound one or more times around the pipe 1, beyond the ends of the tubing 10, as illustrated at 15, 15.

If greater protection is desired for the ends of the fin structure, flanged cup-like elements 20 may be employed to fit within the ends of the casing tubing 10b around the pipe 1a, with a disc-like body 21 having a central opening to receive the pipe 1a and to bear against the terminal convolution 2a of the fin structure on the pipe 1a. Each end closure element 20 is preferably provided with an angular flange 22 which normally is flared outwardly, as indicated by broken lines in Fig. 3, and which is forced into the end of the casing tubing 10b for frictionally engaging the inner surface thereof and maintaining the end cup 20 in place. If desired, the outer surface of the annular flange 22 may be provided with an adhesive prior to the inserting of the cup into the end of the tubing, or the cup may be maintained in place by the simple expedient of the common wire staple driven through the flange 22 and the wall of the tube 10a adjacent the end thereof.

For shipping or handling purposes, a number of the individually packaged finned pipe units, each encased within its own protective covering 10, may be assembled, in the manner illustrated in Fig. 4, and bound together by spaced bands 25 of metal, cloth, paper, or any other suitable material.

If desired, an outer protective casing 10c may be formed directly on the finned pipe 1c by winding a heavy tough, preferably creped, paper 26

in laterally overlapping spiral convolutions 27, 27 directly on the outer edges 5c of the fins 2c, as shown in Fig. 5, with substantially one half the width of the strip 26 in each convolution overlapping substantially one half of the width of the strip in the underlying convolution. By winding the protective covering directly on the outer edges of the fins under tension, the wrapping paper will tend to form into small convexities between the adjacently relatively spaced fins 2c thereby connecting the outer edges of the fins and causing the collective bend-resisting strength of the connected fins to offer increased resistance to bending of any of the fins as a result of contact of the wrapping with some extraneous object, much in the same manner as illustrated in Fig. 2.

Throughout the foregoing description and throughout the following appended claims, the casing 10 has been described as "closely fitting" the fin structure. It will be understood, however, that a moderate tolerance between the outside diameter of the fins and the inside diameter of the casing is permissible. For example, the inside diameter of the casing may be as much as one-eighth of an inch larger in diameter than the fin structure, to facilitate the placing of the casing over the fin structure and to take care of variations in the diameter of the fins. This designation has been employed to bring out the general relationship of the casing and the fin structure rather than a tube of such a larger diameter than the fin structure as would permit excessive relative movement between the tube and the fin structure therein that injury to the fin structure would result.

We claim:

1. An article of commerce comprising a length of pipe having on its outer surface a fin structure composed of closely spaced fin-forming elements extending substantially perpendicular to the axis of said pipe with their peripheral edges in substantial axial alinement, and a tubular casing enveloping said pipe throughout the axial length and circumference of the fin structure with the inner surface of said casing engaging the peripheral edges of the fin-forming elements.

2. An article of commerce comprising a length of pipe having on its outer surface a fin structure composed of closely spaced fin-forming elements extending substantially perpendicular to the axis of said pipe with their peripheral edges in substantial axial alinement, and a tubular casing enveloping said pipe throughout the axial length and circumference of the fin structure with the inner surface of said casing engaging the peripheral edges of the fin-forming elements, and means on the pipe at the opposite ends of the fin structure for preventing excessive axial movement of said casing relative to said fin structure.

3. An article of commerce comprising a length of pipe having on its outer surface a fin structure composed of closely spaced fin-forming elements extending substantially perpendicular to the axis of said pipe with their peripheral edges in substantial axial alinement, said fin structure terminating short of the ends of said pipe, a close fitting paper tube thereon and extending throughout the axial length and circumference of the fin structure, and means extending between at least one of the plain ends of the pipe beyond the fin structure and an adjacent end of the close fitting paper tube to prevent axial movement of

said casing with respect to the enclosed fin structure.

4. An article of commerce comprising a length of pipe having on its outer surface a fin structure composed of closely spaced fin-forming elements extending substantially perpendicular to the axis of said pipe with the peripheral edges in substantial axial alinement, and a close fitting paper tube thereon and extending throughout the axial length and circumference of the fin structure on the pipe, the circumferential wall of said tube being of sufficiently low density to become superficially depressed outwardly on its inner surface in line with and by the peripheral edges of the fin-forming elements under excessive pressure externally applied inwardly to said tube, said inner surface under said external pressure developing inwardly projecting convexities intermediate adjacent fin-forming elements and thereby retaining normal spacing of the peripheral edges thereof.

5. An article of commerce comprising a length of pipe having on its outer surface a fin structure composed of closely spaced fin-forming elements extending substantially perpendicular to the axis of said pipe with their peripheral edges in substantial axial alinement, and a tubular casing enveloping said pipe throughout the axial length and circumference of the fin structure with the peripheral edges of the fin-forming elements in frictional engagement with the inner surface of said casing to resist relative axial movement of said casing with respect to said fin structure.

6. An article of commerce comprising a length of pipe having on its outer surface a fin structure

composed of closely spaced fin-forming elements extending substantially perpendicular to the axis of said pipe with their peripheral edges in substantial axial alinement, said fin structure terminating short of the ends of the pipe to provide axially extending end portions free from fin structure, a tubular casing enveloping said pipe throughout the axial length and circumference of the fin structure, and means extending between each of the axially extending end portions and each of the adjacent ends of said casing to prevent axial movement of said casing with respect to the enclosed fin structure.
